STEEL STUDDING

William Griswold Hurlbert, Jr., Niles, Ohio

Application June 12, 1939, Serial No. 278,779

6 Claims. (Cl. 72—115)

This invention relates to steel studding and more particularly to a construction utilizing rolled channels for both the floor and ceiling members, as well as the studs.

A general object of the invention is to provide a stud construction consisting of short rolled channel sections whose intermediate portions may be overlapped, while the opposite end portions are deformed and provided with notches to permit twisting of the stud into interlocking engagement with suitable slots in the floor or ceiling tracks. In that connection, it may be pointed out that the rolled channels constituting the studs may be overlapped in adjustable relation to vary the effective length of the stud, and held in position by wiring or equivalent means.

A further object of the invention is to provide a stud consisting of overlapping rolled sections which may be so arranged as to provide a slot therebetween which provides a nailing base for the attachment of wood or other grounds on either side of the stud, or partition.

With the above and other objects in view which will more readily appear as the nature of the invention is better understood, the same consists in the novel construction, combination and arrangement of parts hereinafter more fully described, illustrated and claimed.

A preferred and practical embodiment of the invention is shown in the accompanying drawing in which:

Figure 1 is a perspective view illustrating the invention.

Figure 2 is a detail side elevation, partly in section and illustrating a modified form of the invention.

Figure 3 is a horizontal cross sectional view taken on the line 3—3 of Figure 2.

Figure 4 is a detail vertical section taken on the line 4—4 of Figure 2.

Similar reference characters designate corresponding parts throughout the several figures of the drawing.

According to the embodiment shown in Figure 1, the invention includes in its organization a floor attaching member or track A and a ceiling attaching member or track B. These elements A and B are preferably rolled channels and are intended to have the edges of their flange portions respectively engage the floor and the ceiling while the webs thereof face each other. As will be observed from Figure 1, the said webs are provided with the fastening receiving openings and with the stud receiving and interlocking slots 2.

The stud is designated generally as C and pref-

erably comprises the short rolled channel sections 3—3. The inner ends of said channel sections 3—3 may be overlapped in nesting relation and are, therefore, slidably related to vary the effective length of the stud. Any suitable means such as the wire 4 may be used for holding the channel sections in the selected adjusted position. The outer ends of the channel sections 3—3 are preferably deformed into substantially tubular formation as indicated at 5. That is to say, 10 the flanges of the channels 3 are bent inwardly toward each other, so that the effective depth or thickness of each end 5 of the channel is less than the width of the slots 2 in the track members A and B. Inwardly of the end of each channel section 3 suitable notches 6 are provided. These notches do not completely pierce the inwardly bent or deformed flanges constituting the portions 5 for the purpose of giving strength to the end of the channel section. The notches 6 15 are preferably of such a depth that the bottoms thereof are of substantially the width of the slots 2 in the track members as will be apparent from Figure 4.

With the deformed and notched formation of 25 the channels 3, it will be apparent that the smallest diameter thereof may be inserted in the slots 2 of the track members, so that the notches 6—6 lie opposite the abutment edges of the slots 2 in the track members. Then, by twisting the channel on its longitudinal axis, the notches may be made to receive the edges of the web of the track adjacent the slot to thus frictionally interlock the stud with the channel.

The foregoing features of construction described in connection with Figure 1 also apply to Figures 2 and 3. However, in these figures, there is the difference that the channel members 3^a constituting the stud C are arranged back to back, so as to provide a space or slot 7 between the members which will serve as a nailing ground. Any suitable and convenient means may be utilized for holding the channel sections 3^a in back to back relation, that is, so that the webs thereof face each other in sufficiently spaced relation to provide the fastening receiving slot 7. According to the example shown in Figure 2, one of the channel sections 3^a is provided with suitable loops 8, welded or otherwise secured to the back of one of the channel sections and into 40 which the other channel section may be slidably inserted. It will, of course, be understood that in this form of the invention, the channel sections may be adjusted longitudinally, one with 45 relation to the other, and that the spacing of the 50

loops or equivalent members 8 may be varied as specifications require. In other words, it is within the scope of the invention to assemble the channel sections 3^a in any suitable manner which 5 will provide a slot for serving as a nailing ground. For example, the overlapped portions of the sections 3^a may be welded together at suitable spaced points with sufficient space left between the webs of the sections to provide a nailing slot.

10 In erecting a stud system in accordance with the present invention, the track elements would be first attached to the floor and ceiling, and then the ends 5 of the channel sections would be inserted in the slots 2 and twisted into interlocking 15 relation with the track elements. According to Figure 1, it will be apparent that one channel section may be first twisted into interlocking engagement with the desired track element and then the other section may be likewise fitted to its 20 related track section. The two sections may be then connected by wiring or other suitable means. In connection with the form shown in Figure 2, it will, of course, be understood that the overlapped portions of the channels 3^a may be located 25 at the bottom of the stud or the top of the stud, depending upon where the nailing ground is desired. In other words, the construction shown in Figure 2 may be inverted. After the stud has been applied to the tracks, metal lath or other 30 plaster base may then be applied to the sides of the stud in the usual manner. Wood or steel grounds may then be secured at the desired locations. It may also be pointed out that the stud, if inverted from the position shown in Figure 2 35 may then have its lower end fitted into a combined nailing ground and holding shoe of the type shown in my co-pending case, Serial #277,291 filed June 3, 1939, which is adapted to fit in a hollow partition track secured to the floor.

40 From the foregoing, it is believed that the present invention provides a simple, practical and accurate construction for erecting channel iron partitions, particularly solid partitions.

I claim:

45 1. A stud construction for partitions and the like, including, floor and ceiling channel tracks arranged to have the edge portions of their flanges engage the floor or ceiling respectively and their webs facing each other, said webs being slotted to provide opposite stud engaging abutments, and a pair of channel elements constituting the stud, the outer ends of each channel element being formed so as to be of less width 50 in one direction than the distance between the edges of the slots in the floor and ceiling channels and provided inwardly of said ends with a pair of transverse notches whereby the said outer ends of said stud channel elements may be twisted into interlocking engagement with the 55 abutments formed by the slot of a related track, and means for connecting the overlapping portions of the channel elements.

60 2. A stud construction for solid partitions and the like, including, rolled floor and ceiling channel tracks arranged to have the edge portions of their flanges engage the floor or ceiling respec-

tively and to have their webs facing each other, said webs being slotted to provide opposite stud engaging abutments, and a pair of rolled channel elements constituting the stud, and adjustably related to vary the effective length of the stud 5 formed thereby, the outer ends of each channel element being provided with a pair of transversely disposed closed notches whereby said outer end of each channel stud element may be twisted into interlocking engagement with the abutments 10 formed by the slots in the floor and ceiling channels, and means for connecting the overlapping portions of the channels forming the stud.

3. A stud construction for solid partitions and the like, including, rolled floor and ceiling channel tracks arranged to have the edge portions of their flanges engage the floor or ceiling respectively and to have their webs facing each other, said webs being slotted to provide opposite stud engaging abutments, and a pair of rolled channel elements constituting the stud and having 15 their web members arranged back to back, and means for connecting the channel sections of the stud to provide a nailing slot therebetween, said channel elements forming the studs having 20 their end portions provided with notches for engaging with the edges of the slots in said track members when the sections are twisted angularly 25 in relation to the track.

4. A stud construction for partitions and the like, including, floor and ceiling channels having their flanges turned respectively toward the floor and ceiling, said channels being formed inwardly of the flanges with opposite stud engaging abutments, a pair of stud constituting channel sections 35 arranged back to back in overlapping relation, means for connecting the stud channels against separation when a fastening is driven in the space between the backs thereof, and means near the ends of said stud sections adapted for twisted 40 interlocking engagement with the abutments of said floor and ceiling channels.

5. A stud construction for partitions and the like, comprising, upper and lower track sections having inwardly facing abutments, a pair of stud 45 forming channel sections having their inner ends arranged back to back in overlapping relation, means for connecting said sections in the zone of overlap to provide a fastening receiving slot, and said stud sections being provided near their 50 outer ends with transversely aligned recesses for registering with said abutments whereby when the stud sections are twisted on their longitudinal axes the said recesses become interlocked with the abutments.

6. A stud construction for partitions and the like, comprising, upper and lower track sections having inwardly facing abutments, stud constituting sections arranged in overlapping extensible relation at their inner ends, and means at the 60 outer ends of the stud sections for interlocking with the said abutments upon a partial rotation of said sections upon their longitudinal axes relative to the tracks.

65 WILLIAM GRISWOLD HURLBERT, JR.
